WALTER McLAREN, OF DAYTON, OHIO.

MOLD FOR ICE-CREAM-CONE MACHINES.

1,232,820.

Specification of Letters Patent. Patented July 10, 1917.

Application filed April 3, 1917. Serial No. 159,479.

To all whom it may concern:

Be it known that I, WALTER McLAREN, residing at Dayton, in the county of Montgomery and State of Ohio, have invented certain new and useful Improvements in Molds for Ice-Cream-Cone Machines, of which the following is a specification.

My invention relates to certain new and useful improvements in molds which have been especially adapted for use in connection with ice cream cone machines of the automatic "Bruckman" type. In machines of this type, the molding devices consist of a pair of separable female mold sections containing the coniform mold cavities which cooperate with cores that are mounted on a core carrier or bar. In operation, the core carrier is raised to lift the cores out of the molds, the core carrier in the Bruckman machine being mounted for pivotal movement on a horizontal axis in the plane of parting of the female molds while the female molds open laterally and are carried on arms that are pivoted on a vertical axis to open somewhat in a "scissors" fashion.

Some difficulty has been experienced in getting the cores to center properly, due not only to the misalignment of the core in entering the mold cavity, but also due, at times, to the excess batter which forms "heads" and tends to force the core out of alignment. In other words, the cores are pressed downwardly from the core bar by springs which allow the cores to yield upwardly to permit escape of steam, or to allow for unevenness in the adjustment of the cores on the core bar; it not infrequently happens that when the cores are descending into the mold cavities in which there is batter, the core heads will not engage properly with the molds; sometimes they will locate themselves more to one side than the other and thus fail to align properly so that the axis of the core and the axis of the female mold cavity will not coincide. This causes the baking of an uneven product, *i. e.*—one side of the cone is thin and the other side thick, and in extracting the cones from the molds they will frequently be broken out at the thin side.

Unless the cone is perfectly made, it is not as desirable a product as otherwise and my present invention therefore especially has for its object to provide a mold construction in which the cones are more perfectly formed than heretofore and in which means are provided for positively centering

the core in the female mold cavity and to close the mouth of the cavity at the core head, save at such predetermined places as are provided through which excess batter and steam or vapor may escape.

Another object of my invention is to provide a mold construction in which the core head will be recessed into the female molds and act as a centering guide for the core and further the invention has for its object to provide means to permit the escape of steam formed in the baking act and expelled as the dough expands to completely fill the mold cavity, the steam's escapeways being also provided for the purpose of confining, as much as possible, the batter escape to these places, so that when the cone is released from the mold it will usually be formed without a ring-like "head" of excess batter, but if any such ring-like "head" is formed, it will be uniformly thin and can be easily trimmed off when the cone passes through the trimmer.

The invention also includes those novel details of construction, combination and arrangement of parts, all of which will be first fully described, then be specifically pointed out in the appended claims, and illustrated in the accompanying drawings, in which:—

Figure 1 is a horizontal section on the line 1—1 of Fig. 3.

Fig. 2 is a top plan view of a portion of a female mold with the core removed.

Fig. 3 is a cross section on the line 3—3 of Fig. 2.

Fig. 4 is a detail elevation of a portion of one of the half mold members looking at the same from the parting plane.

Fig. 5 is a view similar to Fig. 2 of a modified formation of the invention.

Fig. 6 is a detail section illustrating the rise of the core when a great excess of batter is used and oozes out around the entire mouth of the cone to form an annular excess batter "head" and also showing the core with an annular flange for closing the steam escapeways when the parts are closed down normally.

Fig. 7 is a detail plan view of a cone on a reduced scale showing the same as it looks after being discharged from the mold and illustrating the protruding knobs of excess batter which are formed under proper operating conditions.

Fig. 8 is a view similar to Fig. 7 illustrating the cone as it looks in the event

that a slight excess amount of batter is put into the mold, enough to form a thin fin around the mouth of the cone between the knobs.

- 5 In the drawings, in which like numerals and letters of reference indicate like parts in all of the figures, 1 represents the half-mold members of the female mold section which include the half dies or coniform cavities 2 which are usually provided with filigree work, save at their upper ends, where they are counterbored at 3 to form the mouth strengthening bead or additional thickness of the cone. In my invention also the molds 10 are counterbored rather deeply, as at 4, to receive the vertical annular wall or surface 8 of the core head which snugly fits the counterbore 4 when the parts are assembled, see Fig. 3.
- 20 5 designates steam escapeways which are recessed into the female molds and extend down with their lower surfaces 6 below the plane of the seat surface 17 of the counterbore 4 so as to always effect communication 25 with the interior space 3 of the molds when the core 7 is in place, see Fig. 3.

The core 7 is of the usual construction, save that it is provided with a head to fill the counterbore 4, the head including the 30 vertical annular surface 8 and the horizontal bottom surface 8^x which rests on the surface 17, the corner being beveled as at 9 to aid in the ready entering of the core 7 into the mold and also to provide an annular steam escape space 10 to effect communication between the several steam escapeways 5 and thus equalize the pressure of escaping steam as much as possible. The core is also usually provided with a flange 11 to fit over 40 the upper face of the mold 1 and this flange may be of a diameter such as to expose a portion of the escapeways 5, see Fig. 1, or it may be of a diameter to close such escapeways when the core is in position in the 45 mold, see Fig. 6. When the form shown in Figs. 1 and 3 is employed the steam will always have a free escape to atmosphere without raising the core in the mold but where the flange 11 is of a diameter sufficient to close the escapeways 5 the core will have to rise slowly to open same and permit escape of steam (see Fig. 6) in which event if a considerable excess of batter is used it will flow onto the surface 17 between the 50 surfaces 8^x-17 and form a thin ring-like film or head around the cone and also form the protuberance at the steam escape pockets 15.

In Figs. 6 and 7, 12 designates the batter 60 forming the cone proper, and 13 designates the mouth of the cone which is of thicker material for strengthening purposes. That portion of the batter which forms the thin annular ring-like head is indicated by 14 and

that portion which forms the vertical extension or protuberance is designated by 15 while 16 indicates the batter which has flown entirely to the outside and forms an additional knob on the protuberance 15.

When the molds are open to discharge 70 the cone, the cone drops through trimmer tubes which remove the excess batter or heads and when this consists only of the knobs 14-15 (see Fig. 7) it will be noticed that there is very little waste produced and the trimming knife generally has to cut only at the places where the knobs are located, thus leaving the mouth of the cone with a smoother finish than would be the case were it necessary to trim off an entire annular "ring-like head."

When the batter is somewhat in excess of the amount that can be taken care of by the vents, a thin fin forms around the mouth of the cone between the knobs or protuberances, due to a slight rising of the core on expansion of the batter, which permits the batter to ooze in a thin fin-like sheet between the surfaces 8^x and 17 (see Fig. 8). When the ideal condition exists (and it is 90 the ideal which I desire to approach as closely as possible) the cones come out as indicated in Fig. 7.

I find that by the use of my invention a larger number of cones per given amount of batter can be manufactured than has been the case heretofore under the old practice, where the excess batter formed a considerable "head" that had to be removed before the cone was completed as a commercial article and thus the expense of manufacturing the cones is accordingly reduced.

From the foregoing description, taken in connection with the accompanying drawings, it is thought the complete construction, 105 operation and advantages of my invention will be readily understood by those skilled in the art.

What I claim is:—

1. A pair of separable female mold sections each having a half cone cavity and provided with a counterbore at the top, said counterbore having an annular wall, a core adapted to enter said cavity and partially fill the same, said core having a head provided with an annular surface to snugly fit said counterbore, said female mold sections having steam escape and overflow batter-concentrating passages registering with said counterbore.

2. A pair of separable female mold sections each having a half cone cavity and provided with a counterbore at the top, said counterbore having an annular wall, a core adapted to enter said cavity and partially fill the same, said core having a head provided with an annular surface to snugly fit said counterbore, said female mold sections

having steam escape passages registering with said counterbore and extending below the same to register with the cone cavity.

3. A pair of separable female mold sections each having a half cone cavity and provided with a counterbore at the top, said counterbore having an annular wall, a core adapted to enter said cavity and partially fill the same, said core having a head provided with an annular surface to snugly fit said counterbore, said female mold sections having steam escape and overflow batter-concentrating passages registering with said counterbore, said core having an annular flange extending over said steam escape passages.

4. A pair of separable female mold sections each having a half cone cavity and provided with a counterbore at the top, said counterbore having an annular wall, a core adapted to enter said cavity and partially fill the same, said core having a head provided with an annular surface to snugly fit said counterbore, said female mold sections having steam escape passages registering with said counterbore and extending below the same to register with the cone cavity, said core having an annular flange extending over said steam escape passages.

5. A pair of separable female mold sections each having a half cone cavity, and having a counterbore provided with a vertical annular wall above the cone cavity, a core adapted to enter and partially fill said cone cavity and including a head extended above the cone cavity to fit within said counterbore and substantially close the cone cavity and center the core, said female mold sections having steam escape pockets registering with said counterbore and with said female mold cavity.

6. A pair of separable female mold sections each having a half cone cavity, and having a counterbore provided with a vertical annular wall above the cone cavity, a core adapted to enter and partially fill said cone cavity and including a head extended above the cone cavity to fit within said counterbore and substantially close the cone cavity and center the core, said female mold sections having steam escape ports registering with said counterbore and with said female mold cavity, said core having an annular flange adapted to extend over the steam escape ports.

7. In a baking apparatus, the combination with the female mold having a mold cavity and a counterbore at the outer end of

said mold cavity registering with said mold cavity, a core member adapted to enter said mold cavity and partially fill the same, said core member having an enlarged head provided with an annular wall to enter and fit said counterbore to substantially close the outer end of the mold cavity, said mold having steam escape recesses registering with the counterbore and with the mold cavity beneath the core head.

8. In a baking apparatus, the combination with the female mold having a mold cavity and a counterbore at the outer end of said mold cavity registering with said mold cavity, a core member adapted to enter said mold cavity and partially fill the same, said core member having an enlarged head provided with an annular wall to enter and fit said counterbore to substantially close the outer end of the mold cavity, said mold having steam escape recesses registering with the counterbore and with the mold cavity beneath the core head, said core head having its corner beveled to facilitate entrance into the counterbore and having an annular stop flange designed to rest on the top of the female mold when the core is in place.

9. In a baking apparatus, the combination with the female mold having a mold cavity and a counterbore at the outer end of said mold cavity registering with said mold cavity, a core member adapted to enter said mold cavity and partially fill the same, said core member having an enlarged head provided with an annular wall to enter and fit said counterbore to substantially close the outer end of the mold cavity, and steam escape vents for permitting the escape of steam from the mold cavity without displacing the core.

10. In a baking apparatus, the combination with the female mold having a mold cavity and a counterbore at the outer end of said cavity registering with said mold cavity, a core member adapted to enter said mold cavity and partially fill the same, said core member having an enlarged head provided with an annular wall to enter and fit such counterbore and substantially close the outer end of said mold cavity and steam escape vents in the annular wall of the counterbore for permitting the escape of steam from the mold cavity without displacement of the core, said vents also functioning to concentrate the escaping excess batter at definite predetermined locations.

WALTER McLAREN.
